UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE-APPENDAGE.

52,461.

Specification for Design.

Patented Sept. 17, 1918.

Application filed March 18, 1918. Serial No. 223,237. Term of patent 14 years.

To all whom it may concern:

Be it known that I, ARTHUR W. WADSWORTH, a citizen of the United States, residing at Fort Thomas, in the county of Campbell, in the State of Kentucky, have invented a new, original, and ornamental Design for Watchcase-Appendages, of which the following is a specification, reference being had to the accompanying drawing, forming part thereof.

In the drawing:

Figure 1 is a side elevation of a watch-case appendage embodying my design, its relation to the case proper being indicated by a conventional showing of the latter by dotted lines;

Fig. 2 is a similar edge view thereof;

Fig. 3 is a similar top view thereof;

Fig. 4 is a vertical cross-section through

the bow on a plane corresponding to line 4—4 of Fig. 1;

Fig. 5 is a cross-section through one side of the bow on a plane corresponding to line 5—5 of Fig. 1;

Fig. 6 is a horizontal cross-section through the bow on a plane corresponding to line 6—6 of Fig. 1; and

Fig. 7 is a horizontal cross-section through the pendant on a plane corresponding to line 7—7 of Fig. 2.

I claim:

The ornamental design for a watch-case appendage, substantially as shown.

ARTHUR W. WADSWORTH.
